UNITED STATES PATENT OFFICE.

FREDERICK W. SEA, OF CHICAGO, ILLINOIS.

PHONOGRAPH-RECORD ALBUM.

1,424,781.

Specification of Letters Patent. Patented Aug. 8, 1922.

Application filed December 20, 1920. Serial No. 431,810.

To all whom it may concern:

Be it known that I, FREDERICK W. SEA, a citizen of the United States, and a resident of Chicago, in the county of Cook, State of Illinois, have invented certain new and useful Improvements in Phonograph-Record Albums, of which the following is a specification.

My invention relates to filing devices and more particularly to phonograph record albums, and the invention covers several useful and important features of construction and arrangement, all of which are fully disclosed in the following specification and the accompanying drawings, on which drawings—

Fig. 1 is a plan view of a phonograph record album incorporating the features of my invention, parts being broken away to more clearly show the arrangement.

Fig. 2 is a side elevational view showing the album closed,

Fig. 3 is a side elevational view showing the album open, the opened envelope being shown in vertical section,

Fig. 4 is a side elevational view partly in section showing a modified construction and arrangement,

Fig. 5 is a plan view on reduced scale of one of the envelopes,

Fig. 6 is a plan view of one end of the covering flap showing the arrangement for receiving index cards, and

Fig. 7 is an enlarged sectional view showing the arrangement of the tabs.

In the structure shown the base part 10 is of stiff, preferably rigid material and may be constructed of heavy paper board with cloth covering. Hinged to the rear edge of this base is the back strip 11 to whose upper edge is hinged the main cover part 12. Between the base and cover part is arranged a stack of envelopes 13 all of the same size and offset longitudinally so as to underlap at their front ends and to overlap at their rear ends as clearly shown in Fig. 2. The displacement is just sufficient to leave narrow sections 14 for the application of index and other legends and for providing indicating mechanism to be referred to later. The envelopes are open at their front ends for the reception of records but are closed at their sides. At their rear edges they are closed either entirely or only for a short dis-

tance at their center section to form abutments for the rear ends of the records. The adjacent walls of the envelopes are glued or otherwise secured together along a longitudinal median section, and such securing may extend to the rear edges of the envelopes, or only part way as indicated by the glued areas *x* Figs. 3, 5, and 7. The upper wall of the upper envelope and the lower wall of the lower envelope are respectively secured in a similar manner to the cover and base sections as indicated by the glue areas *y* Figs. 1 and 3, and are held thereby against relative lateral movement. Except for such securing together, the envelopes are free at their sides and rear ends.

Between the upper wall *a* of each envelope and the lower wall *b* of the envelope above is secured a tab 15 (Fig. 7). Such tabs may be secured by the same means which secure the adjacent walls of the envelopes together. The tab for the upper envelope is secured between the top wall of such envelope and the cover 12. With this arrangement when any one tab is grasped and raised the upper wall of the respective envelope together with all envelopes above it are raised, and as the lower wall of the envelope is connected with the upper wall of the envelope below, the envelope is opened wide for the quick and ready insertion or withdrawal of a record.

One of the important objects of my invention is to provide improved means for distributing and taking up the weight of the records, particularly when the album is opened. I provide a supporting block 16 of triangular cross section on the base 10 below the overlapping rear ends of the envelopes. Such block is of triangular cross section with its inclined or sloping surface 17 in position to be engaged by the rear ends of the envelopes so that the envelopes may rest thereon and the load of the records therein supported individually on said block. The angle of the slope on the block is such that the envelopes will be regularly vertically spaced apart a fixed distance sufficient to keep the weight of one record from bearing on the record below. In other words, each envelope with its load is individually supported at its rear edge on the supporting block. With this arrangement, when an envelope is opened preparatory to withdraw-

ing or inserting its record, the weight of the record above is taken up entirely by the supporting block and such upper records are prevented from accumulating their weight 5 on the rear edge of the record to be inserted or withdrawn, so that insertion or withdrawal can be accomplished without interference, and an envelope can always be opened entirely to its rear edge, as clearly 10 shown in Fig. 3. The slope of the block being gradual the envelopes above an opened envelope may readily shift along the slope so that all strain is prevented and the opening of an envelope made as easy as possible. As 15 the base and cover structure are hinged to the back 11 the cover structure and back can swing at the hinged connections to follow the movements of the envelopes and such movement also relieves the envelopes 20 from any strain or interference during opening of any envelope.

It is very desirable that an envelope may be opened sufficiently wide so as to permit the fingers to be readily inserted to grasp 25 a record. It is also very desirable that the record assume such position that it can be easily grasped. This I accomplish by making the envelopes wider than the diameter of the records to be received, and connecting 30 the upper and lower walls of each envelope together at points which are in line with the transverse diameter of the enclosed record when in place. Such fastening means may be in the form of wire stitches 18 and 19 or 35 other mechanism and they are spaced apart a distance which is just sufficient to permit a record to be readily slid between them into place within the envelope. With this arrangement, when a tab is raised the corresponding envelope will be opened wide at its 40 mouth to provide ample room for the insertion of the hand while at the same time the record will be held midway between the upper and lower walls of the envelope by the 45 stitching or other means referred to, as plainly shown in Fig. 3, and the record can then be readily and firmly grasped and withdrawn. The degree of opening of the album is limited by means of a stop cord 20 which 50 is secured to the base and cover parts at one or both sides of the album.

In order to determine whether or not a record is in its envelope, I provide indicating mechanism in the form of a colored area 55 21 on the lower wall of each envelope at the front end thereof, and a sight opening or notch 22 at the edge of the upper wall of the envelope. With this arrangement, when an envelope is empty the colored area will 60 show, but when the record is in place, it will cover the colored area, visibility of the colored area indicating that the record is not in the envelope. The colored areas and notches preferably extend in a row midway 65 between the sides of the envelopes and the

tabs 15 are in a row immediately adjacent. The envelopes may be designated by numbers 23 appearing adjacent the sight notches and if desired, such numbers may also appear on the corresponding tabs.

In order to protect the front underlapping ends of the envelopes and the exposed edges of the records, and also the tabs, I preferably provide a cover section or flap 24 which is hinged to the main cover part 12 at its front 70 edge. When this flap or front cover section is down, it rests against the underlapping ends of the envelopes and against the front edge of the base 10, and preferably locking means are provided for holding the flap 75 closed. As shown, a locking strap 25 is provided which is secured to the base 10 and which has a socket member 26 for receiving the button member 27 on the flap. When the flap is thus locked down, the records are 80 entirely closed and all danger of their slipping out is eliminated. When the flap is 85 open and thrown back the envelopes are accessible for the removal or insertion of records and by providing suitable fastening 90 means such as corner clips 28, an index card 29 can readily be applied on the inside of the flap. Such index card may have on it the numbers corresponding to the numbers 95 of the envelopes together with the titles of the records contained within the envelopes. Such record cards could be of material which would permit erasure so that the titles could be readily changed in accordance with changes in records. If desired, the titles 100 could also be printed or written on the 105 spaces 14 on the underlapping envelopes.

When the closed album is laid in a cabinet flat on a shelf any identification marks or legends on the outside of the flap can readily 110 be read on account of the inclination of the flap, the flap being sufficiently away from the shelf above. Also when the album is set on edge in a cabinet the inclined flap will permit legends thereon to be easily read. The album may also be inserted either flat or on edge in a cabinet with its back section 11 out and to facilitate removal of the album when in this position I preferably provide 115 a finger loop or other pull fitting 30 on the back member.

In Fig. 4 I have shown a modified arrangement. Here, the supporting block 16 instead of having a flat sloping surface, is provided with individual supporting steps 120 31 for the record envelopes. Such steps may be desirable where heavy records such as those for Edison phonographs are contained in the album.

Fig. 4 also shows a modified front cover section, the cover section 32 here shown being of triangular transverse cross section, and it may be a solid block, or, as shown, it may be built up of side and end walls. Its sloping inner surface 33 is parallel with the 125 130

- sloping surface of the block 16 when the album is filled with records, the cover section then forming a square corner front end when the album is closed. When this triangular cover section is swung back against the top 12, legend cards provided on the space 33 can be readily read. A suitable clasp 34 can be provided for holding the front cover section in closed position.
- 5 I thus provide a very substantial, durable, efficient and neat album for records which has a full index thereon of the contents and which index can be readily read by withdrawing the album only a short distance 10 from its supporting shelf and opening up of the front cover section. With only a small clearance space in a cabinet the envelopes can be opened far enough to permit records to be readily inserted or withdrawn. When 15 the album is removed from a cabinet the envelopes can be opened full width and the records withdrawn or inserted with ease and certainty. When the front cover section is locked in closed position the album can be 20 readily carried about with the records fully protected and without danger of their falling out.
- 25 As changes and modifications are possible without departing from the scope of my invention I do not desire to be limited to the precise construction, arrangement and operation shown and described.
- 30 I claim as follows:
1. In a filing device of the class described, 35 the combination of a base, a block secured on said base adjacent its rear edge, said block having its upper surface sloping downwardly toward the front of the base, a plurality of envelopes supported at their rear 40 edges on said sloping surface and regularly spaced apart thereon, said envelopes being all of the same length whereby they will underlap at their front ends, a main cover part extending forwardly from the upper edge 45 of said block over the top envelope, an auxiliary part hinged to the front edge of said main cover part for covering the underlapping ends of said envelopes, said envelopes being open at their front ends for the 50 reception of things to be filed, and means for facilitating opening of said envelopes to give access to the contents.
  2. In a filing device of the class described, 55 on said base adjacent its rear edge and having its upper surface sloping downwardly toward the front of said base, a plurality of envelopes seated at their rear edges on said sloping surface and regularly spaced apart, 60 said envelopes being substantially of the same length whereby they will underlap at their front ends, means for preventing relative longitudinal movement of said envelopes, said envelopes being open at their front 65 ends for reception of things to be filed, and
  3. In a phonograph record album, the combination of a base, a block secured on said base at its rear end and having its upper surface sloping downwardly and forwardly to said base, a plurality of envelopes resting at their rear edges on said sloping surface and regularly spaced apart, said envelopes being substantially of the same 70 length whereby their front ends will underlap, a cover extending forwardly from the upper end of said block to the front end of the upper envelope, said upper envelope being secured to said cover and the lower envelope being secured to the base, said envelopes having their adjacent walls secured together, and tabs at the front ends of said envelopes for facilitating opening thereof, 75 for the reception or withdrawal of records, 80 said block taking up the weight of said records at the rear edges thereof.
  4. In a phonograph record album, the combination of a base, a supporting structure thereon near its rear edge, such supporting structure being of triangular transverse cross section whereby to present inclined surface at its upper side, record-receiving envelopes engaging at their rear edges on said inclined surface and spaced 90 apart thereon, said envelopes being substantially of the same length whereby to underlap at their front ends, means for securing 95 said envelopes against movement in parallel planes relative to each other and to said base, a cover hinged relative to said base and extending forwardly over the top envelope, and tabs at the front ends of said envelopes for facilitating opening thereof.
  5. In a phonograph record album, the combination of a base and a cover, a stack of envelopes between said base and cover, said envelopes underlapping at their front ends and overlapping at their rear ends, the adjacent walls of said envelopes being secured together and the upper and lower envelopes being respectively secured to the cover and base, a supporting structure interposed between the base and cover at their rear ends and providing an inclined surface for receiving the overlapping ends of said envelopes and supporting them, and tabs at the front ends of said envelopes for facilitating opening thereof.
  6. In a phonograph record album, the combination of a base, a cover, a back having hinged connection with said base and cover, a stack of envelopes between said base and cover, said envelopes underlapping at their front ends and overlapping at their rear 105 ends, a supporting structure between said base and cover for the rear edges of said envelopes, said envelopes engaging at different heights on said supporting structure, said envelopes being free at their sides for rela- 110
  7. In a phonograph record album, the combination of a base, a cover, a back having hinged connection with said base and cover, a stack of envelopes between said base and cover, said envelopes underlapping at their front ends and overlapping at their rear 115 ends, a supporting structure between said base and cover for the rear edges of said envelopes, said envelopes engaging at different heights on said supporting structure, said envelopes being free at their sides for rela- 120
  8. In a phonograph record album, the combination of a base, a cover, a back having hinged connection with said base and cover, a stack of envelopes between said base and cover, said envelopes underlapping at their front ends and overlapping at their rear 125 ends, a supporting structure between said base and cover for the rear edges of said envelopes, said envelopes engaging at different heights on said supporting structure, said envelopes being free at their sides for rela- 130

4

tive vertical movement but secured together just sufficiently intermediate their sides to prevent relative lateral movement thereof, and said cover and base being secured respectively to the upper and lower envelopes, and tabs at the front ends of said envelopes for facilitating opening thereof, said supporting structure receiving the weight of the records at their rear ends during opening of the envelopes.

7. In a phonograph record album, the combination of a base, a back hinged to the base at its lower edge, a cover structure hinged at its rear edge to said back, a stack of envelopes between said base and cover structure, said envelopes underlapping at their front ends and overlapping at their rear ends, a supporting structure on said base below the overlapping ends of said envelopes shaped to present seating surfaces to the rear edges of said envelopes, said envelopes being secured against lateral movement relative to each other and to said base but being free for relative vertical movement at their sides, said envelopes being open at the front for the reception of records, tabs for facilitating opening of said envelopes, the front section of said cover structure being hinged to normally cover the underlapping and tabbed ends of said envelopes and to be swung back to expose such ends.

8. In a phonograph record album, the combination of a base, a cover, a back hinged to the base and cover, a stack of record-receiving envelopes between said base and cover, said envelopes regularly overlapping a short distance at their rear ends, a supporting structure on said base below said overlapping ends, the upper surface of said supporting structure receiving the rear edges of said envelopes and causing said envelopes to be spaced vertically a sufficient distance so that said supporting structure will individually support the envelopes and records therein, and attachments at the front ends of the envelopes for facilitating opening thereof.

9. In a phonograph record album, the combination of a base, a cover structure, a stack of record-receiving envelopes between said base and cover structure, said envelopes being secured to each other and to said base and cover structure but free at their edges, said envelopes underlapping at their front ends, the front section of said cover structure being hinged to normally cover the underlapping ends of said envelopes and to be swung back to clear such ends.

10. In a phonograph record album, the combination of a base, a cover, a stack of envelopes between said base and cover, said envelopes being secured together and to said base and cover but being free at their edges, said envelopes underlapping at their front ends, and a flap hinged to said cover for normally covering the underlapping ends of

said envelopes and for clearing such ends when swung back, and supports on said flap for an index card.

11. A phonograph record album comprising a stack of envelopes having their adjacent walls secured together but being free at their sides, said envelopes being wider than the diameter of records to be received, the upper and lower walls of each envelope being secured together inwardly of the sides of the envelope and at opposite points in line with the diameter of the record to be received whereby when said envelope is opened a record therein will assume a position midway between the upper and lower walls of the envelope.

12. In a phonograph record album, a stack of envelopes open at their front ends and secured together at their adjacent walls at points within the sides thereof so as to leave the sides free, said envelopes being wider than the diameters of records to be received, and means for restricting the opening of the envelopes inwardly of their front ends in line with the transverse diameter of the records whereby such envelopes may be opened wide at their front ends and the contained records held spaced away from the upper and lower envelope walls.

13. In a phonograph record album, the combination of a stack of envelopes secured together at their front edges inwardly from the sides thereof whereby said envelopes are secured against relative lateral movement at their sides but are free for vertical relative movement, tabs at the front ends of said envelopes for opening them, said envelopes being wider than the diameter of records to be received, and means for restricting the width of the envelopes a distance inwardly from their front ends, the restricted width being substantially equal to the length of the record diameter whereby envelopes may be opened wide at their mouths and said records will be held away from the upper and lower walls of the envelopes by the restricted width.

14. In a phonograph record album, the combination of a base, a stack of record receiving envelopes on said base, said envelopes being of the same length and offset to underlap at their front ends and to overlap at their rear ends, a supporting structure on said base presenting an inclined surface to the overlapping ends to thereby support the weight at such ends, the adjacent walls of the envelopes being secured together at their front edges inwardly from the sides thereof and the bottom of the stack being secured to said base whereby said envelopes are held against relative lateral displacement, said envelopes being free at their sides to be there separable, tabs at the front ends of said envelopes, a main cover section extending forwardly over the upper

- most envelope, and an auxiliary cover section hinged to the main cover section, said auxiliary cover section normally covering the underlapping ends of the envelopes and when swung back exposing such ends, said auxiliary cover having an inclined lower surface which is parallel with the inclined surface of the supporting structure on the base.
- 5 15. In a filing device of the class described, the combination of a base, a support secured on said base adjacent its rear edge and having an inclined upper surface, a plurality of envelopes seated at their rear edges on said inclined surface and regularly spaced apart, said envelopes being substantially of the same length whereby they will overlap at their front ends, said envelopes being open at their front ends for reception of things to be filed, and means for preventing relative longitudinal movement of said envelopes.
- 10 16. In a filing device of the class described, the combination of a base, a support on said base having a surface sloping upwardly from said base, a plurality of envelopes seated at their rear edges on said sloping surface, and means for preventing relative vertical movement of said envelopes, said envelopes being free at their sides for relative vertical movement.
- 15 17. In a filing device of the class described, the combination of a base, a support secured on said base and having a surface sloping upwardly from said base, a stack of envelopes seated at their rear edges on said sloping surface, means securing the adjacent walls of said envelopes together inwardly of the envelope sides whereby said envelopes are secured against relative lateral displacement but are free at their sides for relative vertical movement, the lower envelope being secured to the base, said envelopes being open at their front ends for reception of things to be filed.
- 20 18. In witness whereof, I hereunto subscribe my name this 16th day of December, A. D., 1920.
- 25

FREDERICK W. SEA.
